UNITED STATES PATENT OFFICE.

THOMAS E. CLARK AND JAMES E. CLARK, OF DETROIT, MICHIGAN, ASSIGNEES TO
CONTINUOUS TRAIN CONTROL CORPORATION, OF DETROIT, MICHIGAN, A COR-
PORATION OF MICHIGAN.

GOVERNOR.

Application filed June 9, 1924. Serial No. 719,002.

To all whom it may concern:

Be it known that we, THOMAS E. CLARK and JAMES E. CLARK, citizens of the United States, and residents of Detroit, Wayne County, Michigan, have invented a new and Improved Governor, of which the following is a specification:

This invention relates to means adapted to be attached directly to the wheels of rail-way vehicles, especially to the wheels of the pilot trucks of locomotives, to control electric circuits, especially those which conduct the currents for energizing the electro-magnets of the air-valves of train-control systems, and the object of our invention is to provide a governor which shall be directly attached to a rotating member of the vehicle, which will be operative irrespective of the direction of rotation, which shall be simple and powerful in construction, and which shall not easily get out of order.

Speed governors for train-control systems heretofore suggested have usually been driven by means of belts or other flexible power-transmitters and by positive gearing. But the flexible power-transmitters are liable to stretch and wear while the gearing is also liable to wear and break. Our invention consists of a governor adapted to be directly attached to the sides of the wheels or other rotating member of locomotives and other railway vehicles and embodies a base-plate, weights slidably mounted on the base-plate and movable against the force of springs by centrifugal force to control switches as these weights move outward and inward.

It also consists of relatively stationary conductor rings co-axial with the wheel on which said base-plate is mounted, contacts connected with said switches and engaging the rings, and means to hold the rings from rotating with the wheel.

It further consists in the details of construction illustrated in the accompanying drawings and particularly pointed out in the claims.

In the drawings, Fig. 1 is an elevation and Fig. 2 is a plan of this improved speed governor in operative position. Fig. 3 is a section on the line 3—3 of Fig. 2 on a larger scale. Fig. 4 is a section of the base and case co-axial with the wheel on which this governor is mounted. Fig. 5 is a similar

section of the entire governor. Fig. 6 is a section of a switch.

Similar reference characters refer to like parts throughout the several views.

In the present construction a base-plate 1 is attached to a pilot wheel 2 of a locomotive by means of studs 3 and nuts 4. A hollow hub or sleeve 5 extends from this base-plate co-axially with the wheel axle 6 and it carries the contacts 7, 8 and 9 which may be built like an ordinary brush holder 65 with electrodes 10 to which the wires to the switches A and B are attached. These switches are operated by weights 12 which are slidable on the pins 13, shown in Fig. 3. While there may be any desired number of 70 these weights, they should be evenly spaced around the hub sleeve 5 in order to balance the structure. We prefer to make these weights in the form of a spool with weight flanges 14 at their outer ends and contact 75 flanges 15 at their inner ends. The springs 16 press against the internal flanges 17 and against the cylindrical nuts 18 which adjust the tension of these springs and also constitute guides for the outer ends of the 80 weights. Lugs 19 on the base-plate 1 limit the outward movements of these weights under centrifugal force and thus prevent undue stresses on the switches.

The switches employed may be of any 85 suitable well known construction. In Fig. 6 we have shown a shell or case 21 and a diaphragm 22 thereon of insulating material which carries the posts 23 and 24 which connect to the contacts 25. A second dia- 90 phragm 26 and the end of the shell support the slidable stem 27 to which is connected the double-cone 28. A spring 29 normally holds the stem 27 outward. Slidable within the case and preferably between the guides 95 30 is a small bridge 31 adapted to engage the contacts 25, as shown in Fig. 6, and within this bridge is an annular coil spring 32 which tightly engages the cone 28 and because of the taper of the inner end of 100 the cone, normally presses the bridge against the contacts 25, by reason of the tendency of the spring to slide down the tapering inner end of the cone. But when the stem is pressed in until the spring has slipped over the hump of the stem, then the spring 105 will slide outward on the outer taper of this double cone and pull the bridge 31 away

from the contacts 25, to the position shown in dotted lines. The bridge will remain in this outer position until the stem has been permitted to slide outwardly a sufficient distance to pull the hump on the stem out through the spring. The stem can therefore move in and out considerable distances without affecting the positions of the bridge and the movements of the bridge will always be rapid. This avoids repeated and unnecessary opening and closing of the switch while the weight is at its intermediate positions and reduces arcing. This switch is well known and has been fully tested in the arts.

The sleeve 5 which carries the contacts 7, 8 and 9 rotates with the wheel. Bushings 36 and 37 within this sleeve support a spindle 38 on which is mounted a sleeve 39 of insulating material which carries three conductor rings 41, 42 and 43 to which the wires 44, 45 and 46 connect, these wires extending through a hollow arm 47 and through a chamber 48 in the spindle. The sleeve 39 may be held in place by a collar 49. The spindle may be formed with collars 51 and 52, one on each side of the bearing bushing 37 which is made of two pieces and held in the sleeve 5 by screws 53.

Instead of the wires 44, 45 and 46 being continuous to the train-control instrumentalities, it may be desirable to divide them within the arm 47 as shown in Fig. 5. A short sleeve 54 has a cap 55 which forces a split wedge 56 into the tapering hole in the bushing 57 to securely grip the cable 58. The ends of the wires are connected by ordinary slip couplings 59. The sleeve 54 is secured to the arm 47 by the U-bolt 60 and nuts 61, the bolt extending below the arm 47 and through holes in the lugs 62 on the sleeve 54.

Figs. 1 and 2 show how one of these lugs 62 also carries a pin 63 which receives one end of the link 64 whose other end carries a pin 65 connecting it to an arm 66 pivoted on the pin 67 carried by a bracket 68 secured to the frame member 69 of the vehicle. We prefer to mount a spring 70 between the nuts 71 on this pin 67 and the bracket 68 so as to permit the outer end of the arm 66 to move up and down a limited distance. The arm and link permit the pilot axle to swing in a horizontal plane relative to the frame as the vehicle passes over curves in the track.

This mechanism thus far described is a speed governor adapted to open and close switches, particularly to regulate the speed of railway trains in connection with train-control systems, and is especially adapted for systems employing radio-frequency currents as set forth in copending application Serial Number 676,014, filed November 21, 1923, which may also embody a three position relay of the type shown in co-pending

application Serial Number 335,941, filed November 5, 1919.

Referring again to Figs. 4 and 5, a shell 132 will be observed secured to the base-plate 1 and engaging a packing disk 133 between the flange 134 on the bearing 37 and the flange 52 on the spindle to prevent the entrance of dust. This shell is taken off when the bolts 136 are removed.

It is evident that the number of switches and of the operating weights therefor may be changed as may be desired and that the speed of the governor necessary to cause the operation of such switches may be accurately fixed by the nuts 18.

While we have described this governor as attached to a pilot wheel of a locomotive, it is evident that it may be secured to any other rotating part of a self propelled vehicle adapted to receive it.

The details and proportions of the several parts of this governor may all be changed by those skilled in the art and the application of this governor to other electrical systems may be made without departing from the spirit of our invention as set forth in the following claims.

We claim:—

1. In a governor, the combination of a rotatable support, a weight radially slidable thereon, a spring to resist the outward movement of the weight, stationary conductor rings adjacent the support, contacts carried by the support in engagement with the rings, a switch mounted on the support and controlled by the weight, and conductors between the contacts and the switch.

2. In a governor, the combination of a rotatable support embodying a sleeve, a weight radially slidable thereon, a spring to resist the outward movement of the weight, stationary conductor rings and a support therefor extending into the sleeve, contacts carried by the sleeve in engagement with said rings, a switch mounted on the rotatable support and controlled by said weight, and conductors between the contacts and switch.

3. In a governor, the combination of a wheel, a base-plate secured thereto, a sleeve attached to the base-plate co-axially with the wheel, a pin extending radially to the sleeve and attached thereto, a weight slidable thereon, a spring to resist the outward movement of the weight, a self-closing switch adapted to be opened by the weight when it moves outward, a spindle extending into said sleeve, means to prevent the spindle from rotating with the sleeve, insulated rings mounted on the spindle, electric conductors connecting to the rings, contact members mounted in the sleeve and engaging said rings, and conductors extending from said contacts to said switch.

4. In a governor, the combination of a

vehicle wheel, a base-plate secured thereto, a sleeve attached to the base-plate co-axially with the wheel, pins extending radially from the sleeve, a weight slideable on each pin, a spring to resist the outward movement of each weight, means to adjust the tension of the springs, means to limit the outward movement of the weights, a self-closing switch adjacent each weight adapted to be opened by said weight when moved outwardly by centrifugal force, a spindle extending into said sleeve, bearing bushings within the sleeve to center the spindle, an arm attached to the outer end of the spindle, means connected to said arm to prevent rotation of the spindle, three electric conductor rings mounted on but insulated from the spindle, conductors extending through the arm and spindle to said rings, three contacts mounted in said sleeve, one in engagement with each conductor ring, conductors connecting one of said contacts to each switch, and other conductors connecting the third contact to both switches.

5. In a governor, the combination of a vehicle wheel, weights mounted thereon adapted to be moved outward by centrifugal force, springs to move the weights inward, a switch for each weight adapted to be opened thereby when moving outward, conductor rings adjacent said weights and means to prevent the rings from rotating, contacts rotatable with said wheel and in contact with the rings, and conductors to carry current to said rings and from the contacts to the switches.

6. In a governor, the combination of a rotatable body and weights mounted thereon adapted to be moved outward by centrifugal force, switches adapted to be opened by said weights, means to so regulate the movement of the weights that the switches will be opened in sequence as the speed of the rotatable body increases, and means to conduct current to the switches.

7. In a governor, the combination of a rotatable body and weights mounted thereon adapted to be moved outward by centrifugal force, switches adapted to be opened by said weights, means to so regulate the movement of the weights that the switches will be opened in sequence as the speed of the rotatable body increases, and means to conduct current to the switches comprising stationary conductor rings and contacts carried by said rotatable body in engagement with said rings.

8. In a governor, the combination of a rotatable body and weights mounted thereon adapted to be moved outward by centrifugal force, switches adapted to be opened by said weights, means to so regulate the movement of the weights that the switches will be opened in sequence as the speed of the rotatable body increases, means to conduct current to the switches comprising stationary conductor rings and contacts carried by said rotatable body in engagement with said rings, and means to limit the outward and inward movement of said weights.

9. In a governor, the combination of a rotatable casing, a weight and supporting means within the casing to permit the weight to move toward and from the axis of the support, a spring to move the weight toward said axis, and an electric switch within the support adapted to be opened and closed by said weight.

10. In a governor, the combination of a rotatable casing, a weight and supporting means within the casing to permit the weight to move toward and from the axis of the support, a spring to move the weight toward said axis, an electric switch within the support adapted to be opened and closed by said weight, stationary conductors within the rotatable support, and means electrically connecting the conductors to said switch.
